United States Patent Office

Des. 212,724
Patented Nov. 12, 1968

212,724

CHECKOUT COUNTER

Gerald D. Ailshire, Arcadia, and Thomas K. Bell, Covina,
Calif., assignors to Modern Village Stores, Inc., El
Monte, Calif., a corporation of California

Filed June 1, 1967, Ser. No. 7,330

Term of patent 14 years

(Cl. D80—2)

FIG. 1

FIG. 1 is a perspective view taken from the top, front and left side of a checkout counter embodying our new design;

FIG. 2 is a perspective view taken from the top, rear and right side thereof; and

FIG. 3 is a top plan view thereof.

We claim:

The ornamental design for a checkout counter, substantially as shown and described.
